UNITED STATES PATENT OFFICE.

VALENTINE SCHUCK, OF NEW YORK, N. Y., ASSIGNOR TO THE SUTRO BROTHERS BRAID COMPANY, OF SAME PLACE.

DESIGN FOR BRAID.

SPECIFICATION forming part of Design No. 28,248, dated February 1, 1898.

Application filed November 9, 1897. Serial No. 657,983. Term of patent 14 years.

To all whom it may concern:

Be it known that I, VALENTINE SCHUCK, a citizen of the United States, residing at New York, in the county and State of New York, 5 have invented and produced a new and original Design for Braid, of which the following is a specification.

This design relates to an ornamental braid having a flat central portion inclosed between a tubular edge and a beaded or corded edge.

The design is illustrated in the annexed drawings, in which—

Figure 1 is a face view of the braid, and Fig. 2 is a sectional or end view thereof.

As shown, the braid comprises a flat central body portion 1, having parallel sides or

surfaces inclosed on one side by a longitudinal tubular or hollow edge 2 and on the other side by a beaded, rounded, or corded edge 3, the whole affording a striking ornamental and characteristic appearance. 20

Having described my design, what I claim is—

The design for a braid substantially as herein shown and described. 25

In testimony whereof I have hereunto set my hand in the presence of two subscribing witnesses.

VALENTINE SCHUCK.
